UNITED STATES PATENT OFFICE.

FREDERICK H. WALLIS, OF MINNEAPOLIS, MINNESOTA.

DESIGN FOR A STREET-LAMP.

42,263.

Specification for Design.

Patented Mar. 5, 1912.

Application filed November 27, 1911. Serial No. 662,773. Term of patent 7 years.

To all whom it may concern:

Be it known that I, FREDERICK H. WALLIS, a citizen of the United States, residing at 2421 Russell avenue south, Minneapolis, in the county of Hennepin and State of Minnesota, have invented a new, original, and ornamental Design for Street-Lamps, of which the following is a specification, reference being had to the accompanying drawing, forming part thereof.

The figure is a perspective view of a street lamp showing my design.

I claim:

The ornamental design for a street lamp, as shown.

FREDERICK H. WALLIS.

In the presence of—

F. D. MERCHANT,
HARRY D. KILGORE.
